PRODUCT SUPPORT ENGAGED IN THE INWARDLY-TURNED LIPS OF A CHANNEL MEMBER

Vincent Fortunato, Valley Stream, N.Y., assignor to Henschel-Steinau Co., Palisades Park, N.J., a corporation of New Jersey

Filed Apr. 29, 1965, Ser. No. 449,456
14 Claims. (Cl. 248—223)

My invention relates to product supports which are engaged in the inwardly-turned lips of a channel member and in particular to those product supports which fit into the price channel members on store shelves and serve to project the product forward of the shelf.

There are many supports which are provided with clamps and shelf extenders which attach to the shelf or to the price channel member on the front edge of the shelf. Most of those which engage the price channel member are used either to support an attention attracting flag or are not easily removed from one position and relocated in another position. Some of these prior art supports use clamps having a locking screw or similar device to hold the support to the shelf or the price channel member. For a long time, a need has existed for a support which will support product as well as an attention attracting flag and which may be easily inserted and removed from the price channel member. Moreover, there has been a need to provide such a support for use as a dispensing bin.

In these days of large supermarkets in which impulse buying represents an important part of the sales volume, it is important to thrust certain merchandise outward from the shelf and toward the customer. Many devices have been used to accomplish this purpose but none of them has permitted the store owner sufficient flexibility coupled with low cost and attractive displays.

Accordingly, it is an important object of the invention to provide a product support which engages the inwardly-turned lips of a price channel member.

It is a further object of the invention to provide such a product support which may be easily installed in and removed from the price channel member.

It is a still further object of the invention to provide such a product support which will support a dispensing bin.

These and other objects, advantages, features and uses will be apparent during the course of the following description when taken in conjunction with the accompanying drawings, wherein:

FIGURE 1 is an exploded view of one form of product support of the invention and a shelf with a price channel member affixed thereto, showing the relationship between the price channel member and the product support;

FIGURE 2 is a front elevational view showing the product support of FIGURE 1 inserted in the price channel member;

FIGURE 3 is a vertical sectional view taken on lines 3—3 of FIGURE 2, viewed in the direction of the arrows;

FIGURE 4 is a view in perspective of a slightly modified form of product support of the invention;

FIGURE 5 is a front elevational view of a further modification of product support of the invention;

FIGURE 6 is a side elevational view of the embodiment of FIGURE 5;

FIGURE 7 is a view in perspective of the embodiment of FIGURES 5 and 6 applied to a product dispenser;

FIGURE 8 is a top view of the product support of FIGURE 7, viewed in the direction of the arrow 8 of FIGURE 7;

FIGURE 9 is a view in perspective of a slightly modified form of product support of the invention;

FIGURES 10 and 11 are perspective views of the prod-

2

uct support of FIGURE 9 applied to two different types of product dispensers; and

FIGURE 12 is a perspective view of a modified version of the product support of FIGURE 9 applied to a differently disposed product dispenser.

In the drawings, wherein, for the purpose of illustration, are shown various embodiments of the invention, the numeral 20 designates a product support of the invention, generally. Product support 20 comprises continuous element 22 which is turned back on itself to form midsection 24 which is preferably provided with lugs 25 and arms 26 whose ends 28 are close to each other. Continuous element 22 is turned back so that arms 26 and midsection 24 are in the same plane and so that the distance between arms 26 and midsection 24 is greater than the distance between the inwardly-turned lips 30 of price channel 32.

Price channel member 32 is suitably affixed to shelf 34. Product support 20 is placed in the price channel member 32 by placing arms 26 under one of the inwardly-turned lips 30 and then forcing midsection 24 toward arms 26 so as to engage the other inwardly-turned lip 30 (FIGURES 2 and 3). The spring tension of continuous element 22 produces an outward thrust of the arms 26 and holds the product support tightly in position in the channel member.

Product on slotted cards may be slid on holder 36 which is welded or otherwise suitably affixed to midsection 24 at points 38. Product support 40 of FIGURE 4 is the same as product support 20 except that it is provided with a single holder 42 which is welded or suitably affixed to midsection 24 at point 44. Holder 42 is normally used to display product on cards which have a single hole and are slid onto the holder.

The product supports 20 and 40 are removed from the price channel member 32 by exerting downward pressure to further shorten the distance between midsection 24 and arms 26 and midsection 24 is disengaged from the upper inwardly-turned lip. Then, it is easy to lift the unit out of the lower inwardly-turned lip.

Product support 50 (FIGURES 5—8) comprises continuous element 23, midsection 24, arms 26 with ends 28, extremities 52 and thin resilient strips 54 and 56. Strip 54 is welded or suitably affixed to midsection 24 and strips 56 are welded to or suitably affixed to arms 26. Extremities 52 are bent out of the plane of midsection 24 and arms 26 so that they can enter slots 58 in dispenser 60. The combination of product support 50 and dispenser 60 is inserted in a price channel member by placing strips 56 in engagement with the lower inwardly-turned lip of the channel member and forcing strip 54 into engagement with the upper inwardly-turned lip of the channel member.

Thus, the product is securely and removably supported forward of the shelf and is thrust before the store customers as they wend their way through the aisles.

In FIGURE 9, there is illustrated a further modification of the invention in which product holder 64 is a continuous element which is welded or otherwise suitably affixed to midsection 24 at points 66. The plane of product holder 66 is substantially parallel to the plane of continuous element 22. Holder 64 is shaped so as to fit into slot 68 of compartment 70 (FIGURE 10) or slot 69 of compartment 71 (FIGURE 11). The product supports of FIGURES 10 and 11 are inserted in the price channel member as described earlier in this specification.

The product support of FIGURE 12 is similar to that of FIGURES 9—11 except that holder 72 which is affixed to midsection 24 at points 73 by welding or otherwise is canted so that it lies in a plane which intersects the plane of continuous element 22. Holder 72 is fitted into slot

74 of dispenser 76 which because of the canting of holder 72 is directed back toward the shelf when the continuous element 22 is inserted in the price channel member as described earlier.

While I have disclosed my invention in relation to specific examples and in specific embodiments, I do not wish to be limited thereto, for obvious modifications will occur to those skilled in the art without departing from the spirit and scope of my invention.

Having thus described my invention, I claim:

1. A product support for engaging the inwardly-turned lips of a channel member having at least two such inwardly-turned lips comprising:

a continuous element turned back on itself so as to form a midsection and two arms; the two arms having their ends adjacent each other and being in the same plane and projecting from the midsection a distance greater than the distance between the first and second inwardly-turned lips of the channel member; the midsection engaging the first inwardly-turned lips of the channel member; the arms adjacent the ends of the continuous element being forced into spring engagement with the second inwardly-turned lip of the channel; and means for supporting a product affixed to the continuous member and projecting therefrom.

2. A product support as described in claim 1 wherein the means for supporting a product is affixed to the midsection of the continuous element and projects outwardly therefrom by an angle of about 90°.

3. A product support as described in claim 2 including at least one lug affixed to the midsection projecting outwardly in a direction away from the two arms to facilitate engagement with the first inwardly-turned lip of the channel member.

4. A product support as described in claim 1 including at least one lug affixed to the midsection projecting outwardly in a direction away from the two arms to facilitate engagement with the first inwardly-turned lip of the channel member.

5. A product support as described in claim 1 wherein a thin resilient strip for engaging the first inwardly-turned lip of the channel is affixed to the midsection of the continuous element and a pair of thin resilient strips are affixed to each arm of the continuous element adjacent the ends thereof for engaging the other inwardly-turned lip of the channel.

6. A product support as described in claim 5 wherein the extremities of the continuous element are bent out of the plane of the midsection and arms and parallel thereto and the means for supporting a product is a receptacle having slits therein to receive the extremities of the continuous element.

7. A product support as described in claim 1 wherein the extremities of the continuous element are bent out of the plane of the midsection and arms and parallel thereto and the means for supporting a product is a receptacle having slits therein to receive the extremities of the continuous element.

8. A product support as described in claim 7 including at least one lug affixed to the midsection projecting outwardly in a direction away from the two arms to facilitate engagement with the first inwardly-turned lip of the channel member.

9. A product support as described in claim 1 wherein the means for supporting a product comprises a second continuous element bent back on itself in a second plane and which is affixed to the midsection of the continuous element so as to project upward therefrom.

10. A product support as described in claim 9 including a receptacle having a slit therein for receiving the means for supporting a product.

11. A product support as described in claim 10 wherein the plane of the means for supporting a product is parallel to the plane of the continuous element.

12. A product support as described in claim 10 wherein the plane of the means for supporting a product intersects the plane of the continuous element.

13. A product support as described in claim 9 wherein the plane of the means for supporting a product is parallel to the plane of the continuous element.

14. A product support as described in claim 9 wherein the plane of the means for supporting a product intersects the plane of the continuous element.
